UNITED STATES PATENT OFFICE.

EUGENE FOURNIER, OF CHICAGO, ILLINOIS.

AIR MATTRESS OR CUSHION.

SPECIFICATION forming part of Letters Patent No. 624,638, dated May 9, 1899.

Application filed August 30, 1898. Serial No. 689,823. (No model.)

To all whom it may concern:

Be it known that I, EUGENE FOURNIER, a citizen of the United States, residing in Chicago, county of Cook, and State of Illinois, have invented new and useful Improvements 5 in Air Mattresses or Cushions, of which the following is a specification.

My invention relates to improvements in that class of mattresses that is capable of being inflated and deflated; and the object of my improvements is to provide an article of this kind that will be easily portable when deflated and when inflated will be comfortable, in that it will readily conform to the different 10 positions taken by the user and will retain the air under all conditions to which it would be normally subjected. The manner in which I attain these objects is fully set forth in the accompanying drawings, which 15 form a part of this application, in which—

Figure 1 is a perspective view of my invention in the form of a mattress with a portion removed to show the anchors or fastenings. Fig. 2 is a cross-section of the mattress, and 20 Fig. 3 is a sectional view of the fastening or anchoring device in detail on a large scale.

Like letters indicate like parts in the several views.

My invention consists generally of a rubber 25 bag or like device adapted to be inflated by air introduced through a valve and provided with a covering of ticking or other textile fabric and means for anchoring or quilting the top and bottom.

By reference to the drawings it will be seen 30 that B represents a mattress rectangular in form and made from sheets of rubber cloth suitably secured together to form an air-tight body and with a suitable valve at one end for 35 introducing the air. Entirely enveloping the rubber mattress is a covering A, which is composed of ticking or other suitable textile fabric and conforms in shape to the mattress B.

The covering A is held in place on the mattress 40 and the latter is given a flat, oval, or other form desired by means of stays which are placed at intervals throughout the body of the mattress. These stays are composed of a cylindrical metal disk C, formed with a 45 downwardly-extending hub portion C' and a countersunk face C². The hub C' has its

lower portion flattened and perforated for the reception of a cord, chain, or spring. The upper part of the hub C' is bored longitudinally and the bore threaded to receive a 55 threaded bolt c, having a flat head c'. The bolt c is also bored longitudinally and the bore threaded to admit a screw D. Between the countersunk face of the disk C and the head of the screw D is interposed a flat 60 washer c². The stays consist, further, of chains, cords, or springs d, which are attached to the flat portions D' of the disk C.

In applying the stays I perforate the rubber sheet B, place around the perforation a 65 washer c', and insert therethrough the bolt c, pressing it firmly down onto the washer. I then screw the threaded hub portion of the disk C onto the threaded part of the bolt c until the washer and rubber are forced into 70 the countersunk face of the disk C. The ticking or outer fabric A is then perforated and the screw D inserted therethrough and screwed into the internally-threaded shank of the bolt c' until the head of the latter is 75 firmly pressed on the head of the bolt c and the washer c', thus securing a tight joint between the rubber sheet B and the cover A and adding to the effectiveness of the closure of the opening in the rubber sheet. It will be noted 80 that the screw D has a flat head which is provided on its upper face with a covering of cloth. When the disks, washers, and screws have been secured in the manner described at proper intervals throughout the top and bottom of the mattress, the opposing hub portions C' are connected by means of chains, cords, or springs d, which are drawn sufficiently tight to bring the face of the screws D below the plane of the mattress, or, in 85 other words, the latter is "quilted." In the drawings I have shown the parts d as chains; but it will be apparent that cords may be substituted for the chains. It will also be apparent that I can give the surface of the mattress any desired contour by giving to the parts d different lengths.

Interposed between the top and bottom sheets of rubber is a sheet of cotton cloth E or other suitable material, which is secured 90 to the end pieces e of the mattress. The function of the sheet E is to prevent the two

sheets of rubber from sticking together when the mattress is deflated and rolled up for storing or transportation.

Having thus described my invention, what I claim, and desire to secure by Letters Patent, is—

1. In a device of the character described, the combination with an elastic-fabric bag, of stays consisting of metal disks having a countersunk face and a hub portion, and means for forcing the elastic fabric into the countersunk face of the disks, and means for connecting the opposite hub portions, substantially as set forth.

15 2. In a device of the character described, the combination with an elastic-fabric bag, of stays consisting of metal disks having a countersunk face and a threaded hub portion, a bolt for forcing the elastic fabric into the countersunk face of the disk, and means for connecting the oppositely-extended hub portion, substantially as described.

3. In a device of the character described, the combination with an elastic-fabric bag 25 and a non-elastic-fabric cover for same, of stays consisting of metal disks having a countersunk face and a threaded hub portion, an externally and internally threaded bolt for

forcing the elastic fabric into the countersunk face of the disk, a screw adapted to enter the bolt and secure the non-elastic fabric in place, and means for connecting the oppositely-extended hub portions, substantially as described.

4. In a device of the character described, 35 the combination with an elastic-fabric bag, and a non-elastic cover for same, of a sheet of cloth interposed between the opposing sides of the bag, and means for staying the opposing sides of the bag, substantially as described.

5. In a device of the character described, the combination with an elastic-fabric bag, a non-elastic cover for same, a sheet of cloth interposed between the opposing sides of the bag and stays consisting of metal disks having countersunk faces and threaded hub portion, means for forcing the elastic fabric into the countersunk face and means for connecting the oppositely-extending hub portions, substantially as set forth.

In testimony whereof I affix my signature in presence of two witnesses.

EUGENE FOURNIER.
